(57) **CLAIM**

The ornamental design for a thermotherapy massage apparatus for a sliding bed, as shown and described.

DESCRIPTION

FIG. 1 is a perspective view;

FIG. 2 is a front view;

FIG. 3 is a rear view;

FIG. 4 is a left side view;

FIG. 5 is a right side view;

FIG. 6 is a top view; and,

FIG. 7 is a bottom view.

The broken lines shown in figures illustrate portions of the thermotherapy massage apparatus for a sliding bed that form no part of the claimed design.
